UNITED STATES PATENT OFFICE

101,011

DESIGN FOR A BOTTLE

Lewis H. Scurlock, Chicago, Ill.

Application June 1, 1936, Serial No. 62,912

Term of patent 14 years

To all whom it may concern:

Be it known that I, Lewis H. Scurlock, a citizen of the United States and resident of Chicago, in the county of Cook and State of Illinois, have invented a new, original, and ornamental Design for a Bottle, of which the following is a specification, reference being had to the accompanying drawing, forming a part thereof:

Fig. 1 is a perspective of a bottle showing my new design, showing one side thereof, it being understood that the other side may have the same appearance.

Fig. 2 is a side elevation of said bottle.

Fig. 3 is a plan view of said bottle.

I claim:

The ornamental design for a bottle, as shown and described.

LEWIS H. SCURLOCK.
